United States Patent Office

Des. 207,863
Patented June 6, 1967

207,863

SUGAR DISPENSER OR SIMILAR ARTICLE

Ruediger W. Knott, Corning, N.Y., assignor to Corning
Glass Works, Corning, N.Y., a corporation of New
York

Filed May 5, 1966, Ser. No. 2,186

Term of patent 14 years

(Cl. D44—15)

Fig. 2

Fig. 1

Fig. 4

Fig. 3

FIG. 1 is an elevational view, partly in section, of a sugar dispenser or similar article showing my new design; FIG. 2 is a top plan view thereof;

FIG. 3 is an elevational view of another form of sugar dispenser or similar article showing my new design where-in the upper periphery is provided with a pouring lip; and

FIG. 4 is a top plan view thereof.

The encircling band in FIGS. 1 and 3 is lined for color.
I claim:

The ornamental design for sugar dispenser or similar article, as shown and described.
